UNITED STATES PATENT OFFICE.

FRANK L. FORSTER, OF SHELBYVILLE, INDIANA, ASSIGNOR OF ONE-HALF
TO JACOB A. CONREY, MARY CONREY, AND ALBERT H. HILDRETH, OF
SHELBYVILLE, INDIANA.

JOINT FOR KNOCKDOWN OR SEPARABLE FURNITURE.

SPECIFICATION forming part of Letters Patent No. 692,053, dated January 28, 1902.

Application filed July 10, 1901. Serial No. 67,768. (No model.)

To all whom it may concern:

Be it known that I, FRANK L. FORSTER, a citizen of the United States, residing at Shelbyville, in the county of Shelby and State of Indiana, have invented new and useful Improvements in Joints for Knockdown or Separable Furniture, of which the following is a specification.

This invention relates to certain new and useful improvements in joints for knockdown or separable furniture; and it consists in certain improvements whereby several parts or sections can be separated or knocked down for shipment and can be readily placed together, the joints or connections being such that the parts may be drawn one toward the other to make a tight joint, as will be herein-after set forth.

In the accompanying drawings, which illustrate one embodiment of the invention, Figure 1 is a perspective view showing several parts of a sectional bookcase or like receptacle connected in accord with my invention. Figs. 2 and 3 are sectional views. Fig. 4 is a perspective view of the movable latch-bar detached, and Fig. 5 is a sectional view showing four pieces or parts connected by a single latch-bar.

Referring to the accompanying drawings, A indicates the several sections or parts of a knockdown article of furniture—for instance, a section of a bookcase—and in the make-up of such an article one of the parts has plowed into one of its edges a longitudinal groove or recess a, which is partially occupied by a filling-piece b, thus providing a longitudinal opening which is rectangular in cross-section below the filling-piece. In line with the opening a is a cylindrical recess c of a larger diameter than the rectangular aperture, the same being for the reception of a cylindrical nut, which is held therein so as to be turned by a suitable key. At intervals the part having the longitudinal aperture is provided with cylindrical openings d, which extend from the outer edge and intersect the aperture a.

The latch-bar B is preferably rectangular in cross-section and presents two strips of

metal e e', one of them having therethrough slots f f', and out of line with these slots are blocks g g', with beveled ends, and these blocks serve to hold the plates together. When three pieces are to be connected by a single latch-bar, additional blocks g' may be provided. Upon one end of the latch-bar is a bolt h, which is engaged by a cylindrical nut i, having a circumferential recess into which lies a retaining-plate k, said plate being attached to the section having the longitudinal aperture a, and said plate and the front edge may be covered by a suitable molding-strip. One of the sections of the structure may have attached thereto a plate l, which is let into the edge of the section and is retained by screws, this plate having several cylindrical projecting portions which are adapted to enter the cylindrical apertures d, and said parts have hooks m, with beveled edges, the hooks being of such size that they may be passed through the slots f to be engaged by the latch-bar when the same is moved. The other piece or pieces of the article of furniture may be recessed to receive plates n, which plates carry hooks o, which are beveled to engage the beveled edges of the blocks g, and these hooks pass through slots p in the section having the sliding latch-bar. The construction shown may be varied and the nut which moves the latch-bar can be operated by a suitable key, and said nut by preference will be located at the back of the article of furniture to which the fastening is applied. The latch-bar may be made as shown or from a rectangular piece of tubing.

Having thus described my invention, what I claim as new, and desire to secure by Letters Patent, is—

1. Means for connecting several parts of knockdown furniture, consisting of a part which has near one of its edges a longitudinal aperture, two or more of the walls adjacent to the aperture having openings, a latch having a threaded end portion, the latch being housed in the aperture, a nut which engages the threaded portion of the latch and is held against displacement, parts for engagement with the hereinbefore-mentioned part,

said parts having hooks which are adapted to be placed in the path of the latch so as to be engaged thereby, substantially as shown.

2. A joint for connecting several parts of furniture, one of the parts having an aperture in which is housed a latch-bar, said latch-bar having through different faces a plurality of catch portions, threads on one end of the latch-bar, a nut which engages the threads and moves the latch-bar lengthwise when turned, openings or recesses through the walls of the aperture in which the latch-bar is housed, the parts or members which are adapted to be attached to the first-mentioned part having attached thereto projecting hooks of such length as to pass through the recesses in the walls of the aperture in which is housed the latch-bar and engage said latch-bar, substantially as shown and for the purpose set forth.

3. Means for connecting several parts of furniture one to the other, consisting of a many-sided latch-bar housed within one of the parts to be longitudinally movable with respect to said part, the latch-bar having catches for hooks in several of its faces, the other parts of the furniture having hooks with beveled faces for engagement with the catches of the latch-bar, so that the several parts will be drawn one toward the other and held positively in locked engagement by the latch-bar.

In testimony whereof I have hereunto set my hand in presence of two subscribing witnesses.

FRANK L. FORSTER.
